Maytag Company, Newton, Iowa, a corporation
of Delaware

Application November 29, 1945, Serial No. 124,201

Term of patent 14 years

(Cl. D67—3)

To all whom it may concern:

Be it known that I, Laurier Carrière, a citizen of the United States, residing at Rockford, in the county of Winnebago and State of Illinois, have invented a new, original, and ornamental Design for Frozen Food Locker or Similar Article, of which the following is a specification, reference being had to the accompanying drawing, forming a part thereof.

In the drawing:

Figure 1 is a perspective view of a frozen food locker or similar article, with the drop leaves in lowered position, embodying my new design;

Fig. 2 is a perspective view of the same with the drop leaves in raised position; and

Fig. 3 is a view in end elevation thereof.

I claim:

The ornamental design for a frozen food locker or similar article, substantially as shown and described.

LAURIER CARRIÈRE.
